UNITED STATES PATENT OFFICE.

PAUL J. SIMMEN, OF OAKLAND, CALIFORNIA.

ELECTRIC BLOCK-SIGNAL SYSTEM.

No. 903,796.

Specification of Letters Patent.

Patented Nov. 10, 1908.

Application filed January 28, 1907. Serial No. 354,382.

To all whom it may concern:

Be it known that I, PAUL J. SIMMEN, a citizen of the United States, residing at Oakland, in the county of Alameda and State of California, have invented new and useful Improvements in Electric Block-Signal Systems, of which the following is a specification.

This invention relates to electrical block systems for railways, being an improvement upon the electrical block signal system for which a United States patent was granted to me, May 1st, 1906, No. 819,677.

The object of the present improvement is to render such a system capable of being used in connection with an electric railroad operated by a continuous current, so that the return circuit for the car propulsion current passes through both rails of the track-way.

In the accompanying drawings, Figure 1 is a diagrammatic view of a track equipped with my improved signal system, operating on trains running in either direction; Fig. 2 is an enlarged detail view of a portion of the track shown in Fig. 1; Fig. 3 is a still more enlarged view of a small portion of such track; Fig. 4 is a diagrammatic view of a locomotive cab, showing the circuit therein; Fig. 5 is a side view of the same to show the contact shoe.

Referring to the drawings, 1 indicates an electrically continuous rail of the track. The other rail of the track is divided into sections 2, which are electrically separated from each other, as shown at 3, the adjacent ends of said sections being connected however by an electrical conductor 14 arranged as shown at 15 to form an inductive resistance offering sufficient impedance to prevent the passage between adjacent section ends of the alternating signal current, but of low enough ohmic resistance to afford a path for the continuous car propulsion current of a conductivity equal to or greater than that of the rails.

The general construction of my system is the same as in my patent above referred to. Thus, there are three contact rails 4, 5, 6, at one side of the track respectively connected by the wires 7, 8, 9, with the sections in advance, and each section 2 is connected with a contact rail 34 on the other side of the track and the contact rails 35, 36, at the other side of the track are respectively connected by

the wires 38, 39, with the contact rails 34, 35 in advance. The contact makers 10, 11, 12, are provided, as before, to contact with the rails 4, 5, 6, respectively but now lead by the wires 20, 21, 22, through the switches 23, 24, 25, to a source of alternating current 26, thence the currents pass to the signals 29, 30, 31, and by the wire 32, and wheel axle 33, to the rail sections 2 all as before. Also the shoes 44, 45, 46, may be provided, as before, adapted to contact with the rails 34, 35, 36 respectively connected with the switches 23, 24, 25, by the wires 47, 48, 49. It will be seen that with this arrangement should there be a train upon a section of the track in advance when the locomotive arrives at the end of any section so that the contact-maker 10 contacts with the rail 4 at the end of said section then the engineer will be apprised thereof by the closure of the following circuit; contact-maker 10, wire 20, switch 23, alternator 26, signal 29, wire 32, wheel-axle 33, all in the locomotive of the train in the rear, thence by the rail 1 to the train in advance, the wheel-axle thereof, section 2, wire 80 7, the wheel-axle thereof, section 2, wire 7, and contact-rail 4. Thus the signal 29 is actuated. In like manner should there be a train on the next section but one in advance at the time of arrival of the succeeding 85 train at the end of any section a similar circuit will be closed through the rail 5 and contact-maker 11, actuating the signal 30, and in like manner a signal 31 will be actuated should there be a train on the next section but two in advance. It will readily be seen that this system can be extended to any number of sections by providing a proper number of contact-rails and contact-makers.

The word "rail" in the claims is to be 95 understood as sufficiently broad to include any piece of metal which will make contact with a moving contact on a train for a sufficient length of time to give the desired signal or other effect.

In applying the electrical block signal system of my patent above referred to to an electrical car line it is necessary that the return current for propelling the car should pass by one rail only, viz., the continuous rail 1. It is desirable for many reasons that both rails be used to transmit this return current. My present invention permits this to be done in all cases where a continuous current is used for propelling the 110

car, without interfering with the operation of said block system used with an alternating signaling current.

I claim:-

- 5 1. In an electrical block-signal system for railways, the combination of an electrically continuous rail of a track, sections of the other rail of the track connected only by conductors forming inductive resistances to
- 10 permit the passage of a continuous current and prevent the passage of an alternating current, a contact rail, arranged adjacent to each such section at a convenient point therefor, an electrical connection between each
- 15 contact rail and a section in advance of the section to which it is adjacent, a contact maker carried by the locomotive, a signaling device carried by the locomotive corresponding with the contact maker, a circuit through
- 20 the signal device to the wheel-axle, and means for supplying an alternating current to said circuit, substantially as described.
2. In an electrical block-signal system for railways, the combination of an electrically continuous rail of a track, sections of the other rail of the track, connected only by conductors forming inductive resistances to
- 25 permit the passage of a continuous current and prevent the passage of an alternating current, a group of contact rails, arranged adjacent to each such section at convenient points therefor, an electrical connection between each member of said group and sections in advance of the section to which they
- 30 are adjacent, a corresponding group of contact-makers carried by the locomotive, sig-
- 35 naling devices carried by the locomotive corresponding with the respective contact-makers, circuits through the respective signaling devices to the wheel-axle, and means for supplying an alternating current to said circuits, substantially as described.
- 40 3. In an electrical block-signal system for railways, the combination of an electrically continuous rail of a track, sections of the other rail of the track, connected only by conductors forming inductive resistances to
- 45 permit the passage of a continuous current and prevent the passage of an alternating current, a series of contact-rails adjacent to
- 50 each such section at a convenient point thereof, an electrical connection between the first member of said series with the next section in advance, an electrical connection between each succeeding member of the series with
- 55 the preceding member of the series adjacent to the section in advance, a corresponding series of contact-makers carried by the locomotive, individual circuits through said contact-makers, signaling devices, said circuits
- 60 leading through the axle of the locomotive, and means for supplying alternating currents to said signaling devices, substantially as described.

In testimony whereof I have hereunto set my hand in the presence of two subscribing witnesses.

PAUL J. SIMMEN.
